INVENTOR:

E. G. K. Anderson,

BY Wm. F. Freudenreich *Atty*

UNITED STATES PATENT OFFICE

ERNST G. K. ANDERSON, OF EVANSTON, ILLINOIS, ASSIGNOR TO APPLETON ELECTRIC COMPANY, A CORPORATION OF ILLINOIS

ADJUSTABLE CONNECTER

Application filed September 3, 1929. Serial No. 390,201.

Some electrical outlet boxes are provided with large sleeve-like bosses to permit pipes or conduits of large diameter to be connected therewith. It frequently happens that a small pipe or conduit is required. The object of the present invention is to produce a simple and novel connector by means of which a small pipe may successfully be connected to such a box or to a large sleeve or nipple of any kind and be located in the most advantageous position with respect to the center of the opening in the pipe or nipple.

20

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a side elevation of an outlet box having a large pipe connected to one end and having a small pipe coupled thereto in accordance with my invention, the small pipe being in section; Fig. 2 is a bottom plan view of the parts shown in Fig. 1, the coupling being shown in section; Fig. 3 is a section on a larger scale, taken approximately on line 3-3 of Fig. 2; Fig. 4 is a side view of the divided clamping block; Fig. 5 is a section through the block taken approximately on line 5-5 of Fig. 3; and Fig. 6 is a section taken on line 6-6 of Fig. 5.

Referring to the drawing, 1 represents a box having through a wall thereof an opening 2 surrounded by and coaxial with an externally screwthreaded sleeve or projection 3 of considerable diameter. The interior of the sleeve 3 is in the form of a frustum of a cone, as indicated at 4, the larger diameter being at the outer end of the sleeve. Lying within the sleeve is a block divided lengthwise into two substantially equal parts 5 and 6. The body of the block is in the form of a frustum of a cone 7 that will fit into the chamber or bore in the sleeve. At the large end of the block is a short section whose periphery, as indicated at 8, is also frusto-conical; the small diameter of the frustum being at

the outer end of the block. In other words, the two frusto-conical sections of the block are placed with their bases toward each other. Screwthreaded upon the sleeve 3 is a coupling sleeve 9, reduced in diameter at the upper or outer end to provide a ring-like part 10 that overhangs the block; the part 10 having an inner frusto-conical surface 11 that matches the surface 8 on the block.

It will be seen that when the block is placed in the sleeve or nipple 3 and the coupling sleeve is screwed down upon the same, the two halves of the block will be pressed toward each other by the cooperating inclines.

The block is provided with a hole extending through the same parallel with and eccentric to the central longitudinal axis of the block; one-half of the hole being formed in each half of the block. One-half of the block is also provided with tongues 12 and 13 adapted to enter notches 14 and 15 in the meeting edge of the other half of the block. The opening in the block is enlarged at any suitable point between the ends to form an annular groove 16 leading out from said opening. Slots 17 and 18 are cut into the meeting edges of the two block members in registration with the groove 16, as best shown in Fig. 3. Into the groove 16 and the notches 17 and 18 is laid a U-shaped resilient wire ring 19, the major portions of whose arms are bent into arcs of circles fitting into the groove 16. The tendency of this spring is to open, that is to spread the free ends of its arms apart. The result is that when the spring is assembled between the two halves of the blocks, it tends to push them apart. The pressure is greatest toward the free ends of the spring, so that the spreading pressure on the block is near the periphery on one side, whereas there is no pressure at the diametrically-opposite side; the result being that the spring tends to swing each half of the block about its point of contact with the other half on the side farthest removed from the hole in the block. Therefore when the parts of the block and the spring are assembled, the two halves of the block will be spread apart by the spring to enlarge the opening through

the block and thus permit a pipe or conduit to be freely inserted in the opening.

The opening through the block is preferably reduced in diameter at the smaller end 5 of the block, to provide a flange or lip 20 against which the end of a pipe, such as indicated at 21, may bear when the pipe is inserted in the opening in the block, thereby preventing the pipe from being pushed entirely through the block. Furthermore, the recesses in the block that produce the hole or bore 22 in the latter may be provided with ribs or beads 23 extending transversely of the long axis of the bore and adapted to bite 10 into the surface of the pipe or conduit when the two halves of the block are closed upon the same.

In Fig. 1 the outlet box is shown as resting against a wall W. The large pipe 24 connected to one end of the block lies near the wall. By properly placing the block in the tubular projection 3, the small pipe 21 will also be brought close to the wall. It will be seen that the two halves of the block in Fig. 1 touch 20 each other only at one side of the block. Therefore even a smaller pipe than the pipe 21 may be attached to the outlet box. Furthermore, by partially withdrawing the block from the tubular projection or sleeve 3, the 25 two sections of the block will be spread still farther apart and, therefore, a somewhat larger pipe or conduit than the pipe 21 may be accommodated. In other words, the same block will serve to connect several different 30 small sizes of pipe to the box. By providing an additional block, having a larger bore or hole through the same, a series of large pipes or conduits may be connected to the box.

It will of course be understood that when a 35 pipe such as the pipe 21 is to be connected to the box, the proper conical block will be placed in position, the spring holding the sections spread apart far enough to permit the pipe to enter readily. Then, when the cap 40 is screwed down, the two sections of the block are rocked upon and toward each other until the pipe is gripped tightly between them. It should also be noted that while my improved connecting means permits a pipe such as the 45 pipe 21 to be placed near a wall to which the box is fastened, it also makes it possible to position the pipe at any point along a circle having its center at the center of the block and a radius equal to the distance between 50 this center and the center of the bore or hole in the block.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:—

1. In combination, a tubular member having an outwardly flaring conical bore, a block shaped to fit into said bore and divided longitudinally into a plurality of sections, said sections having in their meeting faces and at one side of the longitudinal axis of the block recesses combining to form an eccentric hole extending lengthwise through the block, and a cap device cooperating with said tubular member to force the block into the same, said cap device having an opening in the end to expose said hole in the block in various angular positions of the block. 70

2. In combination, a tubular member having an outwardly flaring conical bore, a block shaped to fit into said bore and divided longitudinally into a plurality of sections, said sections having in their meeting faces and at one side of the longitudinal axis of the block recesses combining to form an eccentric hole extending lengthwise through the block, and a cap device cooperating with said tubular member to force the block into the same, said cap device having an opening in the end to expose said hole in the block in various angular positions of the block, said cap device and the outer end of said block having cooperating conical faces oppositely inclined with respect to the cooperating conical faces between the block and said tubular member. 75

3. In combination, an externally-threaded tubular member having a bore in the form of a frustum of a cone, a conical block adapted to fit into said bore and divided longitudinally into a plurality of sections; said sections having in their meeting faces recesses combining to form an eccentrically-located hole extending lengthwise through the block, and an open-ended cap adapted to be screwed on said member and force the block into the latter. 80

4. In combination, an externally-threaded tubular member having a bore in the form of a frustum of a cone, a conical block adapted to fit into said bore and divided longitudinally into a plurality of sections; said sections having in their meeting faces recesses combining to form an eccentrically-located hole extending lengthwise through the block, and an open-ended cap adapted to be screwed on said member and force the block into the latter, said cap and said block having cooperating conical faces oppositely inclined with the cooperating conical faces between the block and said tubular member. 85

5. In combination, an outlet box having a tubular projection provided with an outwardly flaring conical bore communicating at its inner end with the interior of the box, a block shaped to fit into said bore and divided longitudinally into a plurality of sections, said sections having in their meeting faces and nearer one side of the block than the other recesses combining to form a hole 90

extending lengthwise through the block, and an open-ended cap cooperating with said tubular projection to force the block into the latter.

- 5 6. In combination, an outlet box having a tubular projection provided with an outwardly flaring conical bore communicating at its inner end with the interior of the box, a block shaped to fit into said bore and divided longitudinally into a plurality of sections, said sections having in their meeting faces and nearer one side of the block than the other recesses combining to form a hole extending lengthwise through the block, and
- 10 10
- 15 15 an open-ended cap cooperating with said tubular projection to force the block into the latter, said cap and said block having cooperating conical faces oppositely disposed with respect to the cooperating faces between
- 20 20 the block and said tubular projection.

- 7. In combination, a tubular member having an outwardly-flaring conical bore, a block shaped to fit into said bore and divided longitudinally into a plurality of sections, said
- 25 25 sections having in their meeting faces nearer one side of the block than the other recesses combining to form an eccentrically-disposed hole extending lengthwise through the block, said meeting faces being grooved across said
- 30 30 recesses and beyond the latter toward the far side of the block, a bent spring member lying in said grooves and tending to spread said sections apart, and an open-ended cap cooperating with said tubular member to force
- 35 35 the block into the latter.

- 8. In combination, a tubular member having an outwardly-flaring conical bore, a block shaped to fit into said bore and divided longitudinally into two sections, said sections
- 40 40 having in their meeting faces and located nearer one side of the block than the other recesses combining to form a hole extending lengthwise through the block, said meeting faces having tongues and grooves at opposite ends to hold said sections against relative longitudinal displacement, there being spring receiving grooves in said faces extending transversely across said recesses and beyond the latter toward the far side of the block,
- 45 45 50 a U-shaped spring having its free ends lying in those portions of the grooves crossing the recesses and its loop portion in those portions of the grooves lying beyond the recesses, and an open-ended cap cooperating with the said
- 55 55 tubular member to force the block into the latter.

In testimony whereof, I sign this specification.

ERNST G. K. ANDERSON.
